UNITED STATES PATENT OFFICE.

ELI EPSTEIN, OF BOSTON, MASSACHUSETTS.

CYLINDER-LOCK.

1,102,893.

Specification of Letters Patent.

Patented July 7, 1914.

Application filed February 13, 1914. Serial No. 818,581.

To all whom it may concern:

Be it known that I, ELI EPSTEIN, a subject of the Czar of Russia, residing at Boston, county of Suffolk, State of Massachusetts, have invented an Improvement in Cylinder-Locks, of which the following description, in connection with the accompanying drawing, is a specification, like characters on the drawing representing like parts.

10 This invention relates to so-called cylinder locks and has for its object to provide a novel construction that may be incorporated into any cylinder lock now in common use, and by means of which the lock is made non-pickable.

15 The ordinary cylinder lock can be picked by using a properly-shaped key by which the different two-part tumbler pins can be raised into a position in which the division line between the two parts comes in line with the periphery of the cylinder, and at the same time inserting a thin piece of metal between the cylinder and the walls of the bore of the casing and between the two parts of each pin 20 tumbler as it is brought into proper position, thus holding the outer portion of each pin within the casing. In order to change a lock of this nature over into one which cannot be picked in the above way, I propose to make 25 the cylinder of the lock with a peripheral groove and to provide the casing of the lock with means operating in said groove, which means forms an obstruction to the insertion of a lock-picking implement. I have shown 30 in the drawings some embodiments of the invention which have been selected for the purpose of disclosing the principle thereof, and I will now describe such embodiments 35 and then point out the novel features in the 40 appended claims.

45 Referring to the drawings wherein I have illustrated some embodiments of my invention, Figure 1 is a sectional view through a cylinder lock into which my invention has been incorporated taken on the line $a-a$, Fig. 2; Fig. 2 is a sectional view on the line $w-w$; Fig. 1; Fig. 3 is a view showing a different embodiment of the invention; Fig. 4 is a section on the line $y-y$, Fig. 3.

50 Referring first to the embodiment shown in Figs. 1 and 2, 1 designates the casing of a cylinder lock and 2 the cylinder or plug therein having the usual key-hole slot 3. The casing and the cylinder are provided 55 with aligned recesses 4 to receive the usual two-part tumbler pins that are acted upon

by the springs 6 within the casing as usual. The two parts of each tumbler pin are designated 5 and 7, the portion 5 constituting the part which is received within the casing 60 and the portion 7 constituting the part which is received within the cylinder 2. An ordinary cylinder lock of this nature can be more or less readily picked by means of a lock-picking implement 70 in the form of a strip 65 of thin metal that can be inserted between the cylinder 2 of the lock and the wall of the cylinder-receiving bore in the casing, and a suitable key or other implement by which the tumbler pins can be successively lined 70 up. In picking a cylinder lock with these implements, the end of the cylinder is first drilled, as at 20, to permit the implement 70 to be introduced between the cylinder 2 and casing 1, and then a key of special shape is 75 inserted into the key slot 3 and manipulated to line up the tumbler pins successively, and simultaneously the implement 70 is manipulated so that it will pass between the sections of each tumbler pin as the latter is lined up 80 thereby to hold the outer section 5 back in the casing. By this means all of the various tumbler pins can be lined up and the outer ends thereof can be held back in the recesses 4 of the casing 1 so as to permit the cylinder 85 to be turned.

My invention has for its object to provide a novel construction which can be incorporated into any cylinder lock now in use, and by which the latter may be made entirely non-pickable in the manner above described, and I accomplish this object by providing the cylinder 2 with a peripheral groove and by arranging a barrier or stop in the casing which normally occupies said 90 groove and serves to prevent the passage of an implement 70. In Figs. 1 and 2 I have shown an embodiment of the invention whereby this barrier is constituted by one of the sections 5 of one of the tumbler pins, 100 and in incorporating my invention into a lock I first remove the barrel 2 from the casing, take out the section 7 of one of the tumbler pins from the cylinder and form in the cylinder a groove 8 which intersects 105 the recess formerly occupied by the removed tumbler pin section, and then I fill up the recess with solder or other material 10, and re-insert the cylinder into the casing again. When this is done the section 110 5^a of the tumbler pin corresponding to the plugged recess in the cylinder will assume

the position shown in Fig. 1 in which the lower end thereof partially enters the cylinder but rests against the solder or filling 10. This solder or filling is flush with the 5 bottom of the groove 8 so that the cylinder can be turned as usual when the other tumbler pins are properly lined. With this construction it will be seen that the door can be unlocked in usual manner by the key, 10 for the key will line up the remaining tumbler pins, and that when they are so lined up the cylinder can be turned to unlock the door because the filling 10 comes just flush with the bottom of the groove 8. This tumbler pin section 5^a, however, constitutes a barrier which will absolutely prevent the insertion of an implement 70 past it and will, therefore, prevent the tumbler pins to 15 the left of the barrier from being manipulated by an instrument 70 to pick the lock. I will preferably make the groove 8 so that it extends only partially around the cylinder 2, the ends of the groove being tapered, as shown in Fig. 1, so that by turning the 20 cylinder half way around the latter can be removed from the casing.

In Figs. 3 and 4 I have shown an embodiment of the invention wherein the barrier is in the form of a bar or member 11 extending transversely through the casing and occupying a groove 8 in the barrel. The bar 30 11 and groove 8 can be formed in the lock after the same is made, and when the bar is in place it constitutes a barrier which will 35 prohibit the picking of the lock, as above described. In other respects, the invention shown in Figs. 3 and 4 is the same as that shown in Figs. 1 and 2.

One of the important features of my invention is that it can be incorporated in a lock which is already made, for the locks which are now in use can be readily changed over to make them non-pickable in accordance with my invention by removing the 45 cylinder, forming the groove therein and also either removing one of the cylinder sec-

tions of a tumbler pin and filling up the corresponding hole, as shown in Fig. 1, or by introducing a barrier 11, as shown in Figs. 3 and 4.

In the embodiment shown in Figs. 3 and 4 it is necessary to use a key for operating the lock which has a groove cut across its back corresponding to the groove 8 in the cylinder.

Having described my invention, what I claim as new and desire to secure by Letters Patent is:

1. In a cylinder lock, the combination with a casing, of a cylinder within said casing, 60 said cylinder and casing having tumbler-pin-receiving recesses, two-part spring-actuated tumbler pins in said recesses, said cylinder having a peripheral groove of varying depth extending partially there-around, and a spring-pressed pin carried by the casing and occupying said groove thereby preventing a lock-picking implement from being inserted between the cylinder and the wall of the bore in line with said 65 tumbler pins.

2. In a cylinder lock, the combination with a casing, of a cylinder within said casing, said cylinder and casing having a plurality of tumbler-pin-receiving recesses, 75 two-part spring-actuated tumbler-pins in said recesses, said cylinder having a peripheral groove situated between the two end recesses, and means carried by the casing and occupying said groove thereby preventing a lock-picking implement from being inserted from either end of the lock between the cylinder and the wall of the bore 80 in line with said tumbler-pins.

In testimony whereof, I have signed my name to this specification, in the presence of 85 two subscribing witnesses.

ELI EPSTEIN.
